UNITED STATES PATENT OFFICE.

JOSEPH HERMAN, OF PEORIA, ILLINOIS, ASSIGNOR TO KEYSTONE STEEL & WIRE COMPANY, OF SOUTH BAFTONVILLE, ILLINOIS, A CORPORATION OF ILLINOIS.

APPARATUS FOR DRAWING WIRE.

1,270,946.

Specification of Letters Patent.

Patented July 2, 1918.

Application filed February 7, 1916. Serial No. 76,710.

To all whom it may concern:

Be it known that I, JOSEPH HERMAN, a citizen of the United States, residing at Peoria, in the county of Peoria and State 5 of Illinois, have invented new and useful Improvements in Apparatus for Drawing Wire, of which the following is a specification.

This invention has reference to an apparatus for drawing wire.

One of the objects of the invention is to combine with a drawing block a reel to receive the wire as it is drawn, the reel and block being associated in such a manner 15 that the wire will strip itself from the block onto the reel during the drawing process.

The invention has for a further object to improve the method of drawing wire, which consists in providing a block to receive the 20 wire as it is drawn through a die, the drawn wire stripping itself from the block onto a reel associated therewith, said reel adapted to be removed from the block and inverted and during such removal and inversion of 25 said reel to place another into position in connection with said block, and to pass the drawn wire on the inverted reel again through the die and onto the block, the same stripping itself as drawn onto said second 30 reel, means being provided on each reel capable of being operated when the reel has been inverted to allow the coil of drawn wire to strip itself from the reel and be received onto a truck or other suitable 35 means for transporting the same from the drawing frame.

In the drawings:—

Figure 1 is an elevation, partly in section and partly broken away, showing a 40 portion of a wire drawing frame, block and reels embodying my invention.

Fig. 2 is a cross section as the same would appear if taken on the line 2—2 of Fig. 1.

Fig. 3 is a cross section in plan as the 45 same would appear if taken on the line 3—3 of Fig. 1.

Fig. 4 is a vertical cross section showing in detail the relation of a drawing block and a reel associated therewith, and an additional reel adapted to be moved into cooperative relation with said drawing block when the reel associated therewith is inverted.

Fig. 5 is a plan view of one of the reels.

Fig. 6 is a sectional detail showing an

end view of the means for raising and lowering the reels 14.

Fig. 7 is a detail sectional view showing a band clutch to retard the rotative movement of the reels when one is being moved 60 from coöperative relation with the drawing block and the other is being moved into such relation therewith.

Fig. 8 is a plan view of a part of a drawing frame showing a plurality of drawing 65 blocks and operating means therefor.

Like characters of reference denote corresponding parts throughout the figures.

In the art of wire drawing, that is, the drawing of wire from steel rods, it has been 70 the custom in substantially all of the large mills to rest a bundle of rods against a suitable support, in some cases known as a "flipper", the end of the bundle pointed and passed through a die and the end connected 75 to a block rotatably mounted on a wire drawing bench, said bench having operatively connected thereto a large number of drawing blocks whereby the wire drawing process may be carried on to a large extent, 80 a wire drawer being employed to handle one block, some times more than one. After the first drawing operation of reducing a bundle of rods to a suitable gage, the operator must strip the drawn bundle from the 85 block by lifting it off of the same and for a further drawing operation this bundle of wire is placed on a reel removed from the bench, and the end of the wire passed through a die and again connected to the 90 block and the block rotated to further reduce the bundle of drawn wire to a different gage. To remove the bundle of drawn wire again from the block, it is necessary 95 from the block to lift the bundle therefrom and if it is to be drawn to a different gage the same process is carried on, that is, by placing the drawn bundle of wire on a reel and again passing it through a die and onto 100 the drawing block, and when the wire has been drawn to the desired gage the operator must strip the bundle of wire from the block by lifting it therefrom and removing it to a truck or other conveying means. 105

By my improved apparatus I obviate the unnecessary labor on the part of the operator in lifting the bundles from the block when stripping the same therefrom, the process of reducing the rods and subse- 110

quently the wire from one gage to another being carried on without the operator handling the bundles at all, except to place the wire rods in position and the pointing of 5 the rods and also the wire when attaching the same to the block. By the use of my apparatus, one operator can do the work of two or three operators and therefore the 10 cost of drawing the wire is reduced to a minimum, which is of considerable advantage in view of the close margin at which wire is sold nowadays either as plain wire or when subsequently woven into fence fabric.

15 Instead of the usual form of wire drawing bench, I construct what I term a wire drawing frame which may be of any desired length and of a suitable width, the length and width of the frame being determined by 20 the number of sets of drawing blocks it is desired to mount on the frame, it being understood that the drawing blocks are arranged in two rows throughout the length of the frame. The frame comprises a plurality of vertically disposed supports 1 located at opposite sides of the frame and the vertically disposed supports 1^a located centrally of the frame and equidistant from each other. Said frame further comprises 25 30 the longitudinally extending girders 2, of which there may be as many as desired to give proper strength to the frame, and the transversely disposed channels 3 and 3^a and the transversely disposed angle iron beams 3^b; the channels 3 being the main transverse bracing channels of the frame and connected to the vertically disposed supports 1, and the channels 3^a connect the oppositely disposed girders 2 intermediate the channels 3 and also brace the centrally disposed vertical supports 1^a, and have secured thereto the bearing blocks for the shafts through which power is transmitted from the driving shafts to the drawing blocks. The 40 angle iron beams 3^b are connected to the opposite pairs of vertically disposed supports 1 and serve as a mounting for the dies. 4 designates a driving shaft journaled in suitable boxings 5 mounted upon the channels 3 of the frame, and at spaced distances 50 on said shaft are carried bevel gear wheels 6, only one of which is shown. Each bevel gear wheel 6 is connected with a member 7 forming one of the complementary parts of 55 a friction clutch, the other of such parts designated 8 and being connected to a grooved sleeve 9 having a spline and groove connection with the shaft 4 whereby said sleeve and said part 8 of the clutch may be 60 moved on the shaft so as to cause the part 8 to be moved into friction clutch engaging relation with the part 7, or disconnected therefrom. The bevel gear wheel 6 meshes with a larger bevel gear 10. When the 65 clutch parts 7 and 8 are in engaged relation,

power may be transmitted from the shaft 4 through the gear wheels 6 and 10 to a shaft 11 connected to a drawing block 13.

The drawing block 13 may be of any suitable construction, although I prefer that 70 construction which is shown in Fig. 4, said block having a depending annular body 12. 14 designates reels, a pair of which are associated with each drawing block 13, one of such reels coöperating with the drawing 75 block to receive the drawn wire, and the other adapted to contain a bundle of drawn wire, after the first drawing operation of reducing the steel rods to wire, said wire leading from the second reel through the die onto 80 the drawing block and reel operatively connected thereto. Each pair of reels 14 is carried normally in superimposed relation to each other on a shaft 15, each shaft having a hub 16 rotatably carried on a transversely disposed nonrotatable shaft 17. Each shaft 17 is connected at its opposite ends to certain of the girders 2 and each of said shafts pass through a vertical support 1^a. Each reel is movable longitudinally on 85 its shaft 15, in addition to being rotatably carried thereon, and each reel when it is in operative relation with the drawing block is supported by means which when operated will release the same whereby it may move 90 longitudinally on its shaft 15 to detach it from operative connection with the block 13, and allow the shaft 15 with its two reels to be rotated on the shaft 17, removing the reel in operative relation with the drawing 95 block therefrom into inverted position and placing the lower reel into an inverted receiving position and in operative relation with said drawing block.

The reels 14 comprise an annular skeleton 105 frame composed of the longitudinal bars 18 and the radially disposed bars 19 at one end, and the radially disposed bars 20 at the opposite ends, connected to a central hub 20^a the last mentioned radially disposed bars 20 110 extending out beyond the circumferential surface of the reels formed by the longitudinal bars 18 to provide a rest to receive the drawn wire as it strips itself from the drawing block 13. At that end of each reel 115 formed with the radially disposed arms 19, is provided a bearing 21 for the reel, said bearing having a plate 22 disposed externally of the reel and said bearing is also provided with an elongated sleeve 23 120 through which the shaft 15 is carried. Connected to each sleeve 23 and rotatably carried within each reel, is a frame 24, said frame having handle gripping portions 25, whereby the frame 24 may be oscillated 125 within the reel, the oscillatory movement of the frame being determined by the distance of the spacing between the radial bars 20, and as the frame 24 is oscillated it will in turn oscillate the sleeve 23 on the shaft 15 130

and with it the plate 22, for purposes which will be explained.

In the position in which the drawing block 13 and the reels 14 are shown in the figures, one reel has been moved into position by telescoping one end thereof into the drawing block 13, see Fig. 4, and the same locked into position, in a manner to be explained. In this position of the parts a rod or drawn wire if passed through the die 26 may be secured to a suitable clamp 27, see Fig. 1, attached to a cable 28 secured at one end to a longitudinal bar 18 of the reel. Rotation being imparted to the shaft 11 from the driving shaft 4 will cause the drawing block 13 to rotate, and with it the reel in operative connection therewith, as shown in Fig. 4. This rotation of the drawing block and reel will draw the rod or drawn wire through the die 26, reducing said rod or drawn wire to a suitable gage and causing it to be wrapped around the drawing block 13, and as the drawn wire is received onto said block, it will strip itself from the block in the manner shown in Fig. 1, onto the reel 14, said drawn wire finally resting upon the extensions of the bars 20 on the reel arranged to receive the same. The dies 26 are suitably supported from the angle bars 3^b and when redrawing a drawn wire it is understood other and different gage dies will be used.

The means for holding a reel 14 in operative relation with a drawing block 13 in the manner shown in the figures, particularly Fig. 4, comprise a lever 29, see Fig. 2, fulcrumed at 30 on the shaft 17, said lever having a portion 31 adapted to engage and bear against the hub 20^a of the reel 14 on one side of the shaft 15, to retain it in its elevated position shown in the figures and in operative relation with the drawing block 13. Operatively connected with the lever 29 is a member 32 which corresponds to that portion 31 of said lever, being located upon the opposite side of the shaft 17, and said member 32 is adapted to engage and bear against said hub 20^a of the reel 14 upon the opposite side of the shaft 15. In other words, the part 31 of the lever and the member 32 act as bifurcations of the said lever 29 and coöperate in supporting the reel 14 in operative relation with the drawing block 13. The lever 29 is connected with an operating arm or bar 33, see Figs. 1 and 2, which said arm or bar at one end is provided with a member 34 adapted to engage with stepped cut-out portions 35, 36 and 37 of a plate 38. The arm or bar 33 is pivoted at 39 to the frame and the opposite end of said arm or bar is connected to a lever 40 pivoted at 41 to the frame; said lever formed with a yoke 42 having operative connection with the grooved sleeve 9 to which is connected the clutch part 8. In the

position in which the lever 29 and the arm or bar 33 are shown in the figures, particularly Figs. 1 and 2, the reel 14 is in operative relation with the drawing block 13, and any wire drawn onto said block through its rotation and the rotation of the reel will strip itself onto said reel, the position of the arm or bar 33 being that position when the clutch parts 7 and 8 are in clutch engaged relation, allowing power to be transmitted from the driving shaft 4 through the bevel gear wheels 6 and 10 to the shaft 11, and in turn to the drawing block 13 and the reel 14.

To release the reel 14 from the drawing block 13 to invert the position of said reels shown in Figs. 1, 2 and 4, the operator will move the lever 29 so as to move the portion 31 of said lever and the member 32 from engagement with the hub 20^a of the wheel 14. Such movement of the lever will move the member 34 of the arm or bar 33 from engagement with the stepped portion 35 of the plate 38, permitting the reel 14 in operative relation with the drawing block 13 to drop slightly on the shaft 15, and the release of the member 34 from the stepped portion 35 of the plate 38 will at the same time operate the grooved sleeve 9 to separate the clutch part 8 from the clutch part 7, stopping the rotation of the shaft 11. To completely disengage the reel 14 from the drawing block 13, the operator will move the lever 29 so as to disengage the member 34 of the arm or bar 33 and move it into locking relation with the stepped portion 37 of the plate 38, such movement while stopping the rotation of the shaft 11 connected with the drawing block, will also remove the portion 31 of the lever 29 and the member 32 to a position which will permit the reel 14 to move out of engagement with the drawing block 13, so that the operator may rotate the reels and the shaft 15 on the shaft 17 and invert the positions of said reels. When the reel which is in operative relation with the drawing block 13 is inverted, if some means were not provided for holding the drawn wire on the reel, it would strip itself therefrom, but to prevent this I provide the bars 43 pivoted to the plate 22, said bars 43 adapted to have radial movement imparted thereto by the oscillation of the bearing 21 and said plate 22 so as to withdraw said arms within the circumference defined by that end of the reel on which said arms are carried, or projected beyond the circumference of that end of the reel so as to form a shelf portion to receive the roll of wire, the same then serving the same purpose as the extensions of the bars 20 at the opposite end of the reel. In the position in which the reel is shown in Fig. 4, being that position when the reel is in operative relation with the drawing block, the arms 43 are withdrawn into substantially that position shown in

Fig. 3, and just as soon as the shaft 15 has been swung into a position obliquely to the axis of the shaft 17, in which position the reel 14 is entirely removed from the drawing block 13, the operator will grasp the hand-holds 25 on the frame 24 and oscillate said frame, which in turn will oscillate the sleeve 23 of the bearing 21 and with said bearing 21 the plate 22 to which the said bars 43 are pivotally connected, projecting said bars into the position shown in Fig. 5. Said bars 43 are guided in their movement by the straps or yokes 44, best seen in Fig. 1, which are secured to the longitudinal bars 18 of the reel. With the bars 43 in their projected position, such as shown in Fig. 5, shaft 15 may be completely turned around, inverting the positions of the reels 14, placing in position and in operative relation with the drawing block 13 the empty reel, and with the reel having the drawn wire thereon therebeneath. To secure the empty reel in operative relation with the drawing block 13, the operator will actuate the lever 29 to cause the portion 31 thereof and the member 32 connected therewith to bear against the hub 20^a of the reel and elevate it into operative position, being that position shown in Figs. 1 and 2. This operation of the lever 29 will also release the member 34 from the stepped portion 37, returning it to the stepped portion 35 of the plate 38 and at the same time causing the clutch parts 7 and 8 to reengage and transmit power from the driving shaft 4 to the shaft 11. It is understood that the operator may actuate the lever 29 to release the member 34 from the stepped portion 35 of the plate 38 and cause it to move into the stepped portion 36 of said plate, whereby the clutch parts 7 and 8 may be released to stop the shaft 11, but this slight movement of the lever 29 will not permit the reel to be entirely disengaged from the drawing block 13.

45 To retard and control the movement of the shaft 15 and the reels 14 when said shaft is being turned around and the reels inverted, I provide a friction brake, such as shown in Fig. 7, including the member 45, the friction band 46 and the weighted lever 47 suitably connected to operate said band 46. The member 45 is connected in a suitable manner to the hub 16 of the shaft 15, see Figs. 2 and 7.

55 Assuming that the reels 14 are in operative relation with each other and with the drawing block 13, and the operator wishes to draw a steel rod to a suitable gage of wire, he will pass said rod over a guiding roller 48, through the die 26 onto the drawing block 13, first pointing the rod and securing it to the clamp 27 connected with the reel 14. The operation of the drawing block and the reel will draw the wire and during such drawing operation said drawn wire will

strip itself from the drawing block 13 onto the reel 14. When this operation has been completed, the operator will actuate the lever 29 in the manner previously stated to release the reel 14 from the drawing block 13, 70 rotating the shaft 15 with the reels thereon into a position obliquely to the axis of the shaft 17, when he may actuate the frame 24 to project the bars 43 into wire receiving position, so that when the reels 14 have been 75 inverted the drawn wire will rest on the extended ends of the bars 43. The operator will also actuate the frame 24 of the empty reel so as to withdraw the bars 43 connected to that reel, whereby when the reels have 80 been completely inverted, said empty reel may be lifted into engaging relation with the drawing block 13 and secured in such position. In this position of the reels, with the empty reel in operative relation with 85 the drawing block 13 and the other reel containing the drawn wire thereon, and the operator wishes to again draw said wire to a different gage, he will take the end of the wire, pass it through a guide 49, up and 90 over the guiding roller 48, through a die 26 of a different gage to the one previously used, and cause it to be engaged by the clamp 27 on the empty reel. The parts being in this position and power being imparted from the driving shaft 4 to the shaft 11, the block 13 will rotate and with it the reel 14, drawing the wire from the lowermost reel to the desired gage and onto the block 13 from which it will strip itself onto 95 the empty reel 14.

Assuming now that this operation has been completed, and the wire has been drawn to the desired gage, upon again inverting the reels, placing the empty reel 105 into operative relation with the drawing block and placing the reel with the drawn wire thereon into the lower position, with the bars 43 projected into their outward position, the operator may by actuating the 110 frame 24 withdraw the bars 43, allowing the drawn bundle of wire to strip itself from the reel and be received on a truck or other suitable support, to be transferred to a warehouse, galvanizing room or other 115 place.

From the foregoing description it is obvious that the drawing operation may be carried on first with the rods and then with the subsequent bundles of drawn wire without the necessity of the operator handling the same.

What I claim is:—

1. In an apparatus of the character described, in combination, a wire drawing 125 block, means for rotating said block, a reel, means for placing said reel into operative relation with said block to rotate therewith and to receive the drawn wire which strips itself from the block and onto the reel dur- 130

ing the drawing operation, and means for removing the reel from said block and inverting the reel, to allow the bundle of drawn wire to be stripped therefrom.

- 5 2. In an apparatus of the character described, in combination, a wire drawing block, means for rotating said block, a reel support, a pair of reels carried on said support, said support being invertible so as to
- 10 place first one reel and then the other into operative relation with said block to rotate therewith and to receive the drawn wire which strips itself from the block and onto the reels during the drawing operation, the
- 15 inverting of the reels, allowing the bundles of drawn wire to be stripped from said reels.
3. In an apparatus of the character described, in combination, a wire drawing block, means for rotating said block, a reel, means for placing said reel into operative relation with said block to rotate therewith and to receive the drawn wire which strips itself from the block and
- 25 onto the reel during the drawing operation, means for removing said reel from said

block and inverting the same to allow the bundle of drawn wire to be removed therefrom, and means on said reel which is adapted to be contracted or expanded, when 30 contracted permitting an operative relation between said reel and said block, and when expanded forming a stop for the bundle of wire, and means for operating said contracting and expanding means. 35

4. In an apparatus of the character described, in combination, a wire drawing block having a depending annular body, means for rotating said block, a support, a shaft swingable on said support, a reel on 40 opposite ends of said shaft and rotatably and slidably carried on said shaft, means for holding either of said reels in operative relation with said block to rotate therewith, and means on said reels adapted to act 45 as a stop for the bundle of wire when the reel is inverted, said last mentioned means adapted to be retracted to permit the reels to be moved into operative relation with said block.

JOSEPH HERMAN.
